UNITED STATES PATENT OFFICE.

JOHNATHAN W. CLEM, OF WICHITA, KANSAS, ASSIGNOR OF ONE-FOURTH TO CLINTON H. MONTGOMERY AND ONE-FOURTH TO CLARENCE B. WHITESIDE, BOTH OF WICHITA, KANSAS.

PROPELLER.

Application filed September 27, 1920. Serial No. 412,979.

The object of my present invention is the provision of a simple, compact, strong and reliable variable pitch propeller construction, adapted for use on airships as well as 5 for use on marine vessels.

To the attainment of the foregoing the invention consists in the improvement as hereinafter described and definitely claimed.

10 In the accompanying drawings, hereby made a part hereof:

Figure 1 is a front elevation of an airplane propeller constructed in accordance with my invention.

15 Figure 2 is a plan view of the same.

Figure 3 is a broken detail side elevation, partly in section, of the improvement.

20 Figure 4 is a detail transverse section taken in a plane in rear of the body of the propeller.

Figures 5 and 6 are devices of a modification hereinafter explicitly referred to.

25 Figures 1^a, 2^a and 3^a are views of a second modification hereinafter explicitly referred to.

Similar numerals of reference designate corresponding parts in Figures 1 to 4 to which reference will first be made.

30 Among other elements my novel propeller construction comprises a tubular drive shaft 1, through which is arranged to work a rectilinearly movable adjusting rod 2 which for the sake of lightness is preferably tubular as shown. On the said rod 2 is fixed a 35 circumferentially grooved collar 3 with which is engaged a control lever 4, Figure 3, equipped with a detent 5, arranged for cooperation with a rack 6, whereby the control rod 2 may be adjustably fixed in the 40 positions in which it is placed.

At its outer end the control rod 2 is provided with pintle portions 8. Pivoted on the said pintle portions 8 are links 19, for an important purpose hereinafter set forth.

45 Fixed to the drive shaft 1 at the outer end thereof is a body 10, on which are bearings 11 for rock shaft 12, each of which is provided on its outer portion with a propelling blade 13. The rock shafts 12 are arranged 50 in parallelism and are extended in opposite directions beyond the ends of the body 10. It will also be noted that each rock shaft 12 is provided with a thrust washer or abutment 14, arranged in opposed relation to 55 one end of the body 10, and that at its inner

end each rock shaft is provided with a retaining nut or other appropriate device 15 to prevent displacement of the rock shaft from the body. Fixed to the rock shaft 12 at intermediate points in the length 60 thereof are cranks 16 which are arranged to play in and be held against lateral deflection in the body 10, the said body 10 being bifurcated at 17 for the play of the cranks. The said cranks 16 are pivotally connected 65 at 18 to the links 19, which are arranged upon opposite sides of the rod 2 as shown in Figure 3, and consequently it will be seen that said cranks 16 will be held against lateral deflection; also, that endwise movement of the control rod 2 will be attended by turning of the rock shafts 12 about their axes. The shaft 1 and rod 2 are adapted 70 to rotate together, and manifestly power may be applied to either.

75 It will be apparent from the foregoing that in the starting of an aeroplane the propeller pitch may be set for pulling, much after the manner of throwing an automobile into the first gear. Then after the aeroplane 80 has gained a speed of say from 30 to 40 miles an hour, the aviator by the use of the control lever can increase the pitch of the blades, and can regulate the blades at will while in flight. Again when driving against 85 heavy winds the aviator may decrease the pitch of the blades, or when travelling with a strong wind can set the blades for a heavy pitch drive giving the blades more hold or purchase on the air.

90 It will also be apparent that the aviator is enabled to vary the pitch of the blades to meet any condition that may arise while the aeroplane is in the air or on the ground or on a body of water.

95 While designed more particularly for use on aeroplanes, my novel propeller construction may manifestly be used to advantage on other airships as well as on marine vessels.

100 In the modification shown in Figures 5 and 6, the control rod 2 is provided at its outer end with a T-head 7, and the links 19^a are connected to pintle portions 8 on the ends of said head 7; also, the cranks 16^a are disposed at the outer sides of the bearings 11.

105 The modification shown in Figures 1^a, 2^a and 3^a is in the form of a unit applicable to the flanged end 20 of a drive shaft 1^a. The 110

said unit is shown as made up of a shaft 1^b flanged and bolted to shaft 1^a, a collar 3^a splined on said shaft 1^b, a body 10^b on the shaft 1^b parallel shafts 12^b journaled in 5 bearings 11^b on the head 10^b and each carrying a propeller blade 13, cranks 19^b on the shafts 12^b, and links 16^b interposed between the collar 3^a and said cranks.

Having described my invention, what I 10 claim and desire to secure by Letters Patent, is:

In a propeller construction, a tubular drive shaft, a rectilinearly movable adjusting rod slidably mounted in said shaft, pintles 15 projecting from opposite sides of the rod at one end thereof, a body member attached to the end of the tubular drive shaft, said body being bifurcated upon one side to

form spaced bearings, rock shafts mounted in said bearings upon opposite sides of the 20 rod and extending across one face of the body, crank arms attached to the rock shafts midway of the bearings and in alignment with the rod, propeller blades at the outer ends of said rock shafts extending from opposite ends of the body out of longitudinal alignment with each other, links upon 25 opposite sides of the rod forming pivotal connection between the pintles on the rod and the cranks, and a control lever having a connection with the movable rod whereby to impart movement to said rock shaft for imparting rotative movement to said propeller blades.

In testimony whereof I affix my signature.
JOHNATHAN W. CLEM.
